UNITED STATES PATENT OFFICE.

WILLIAM R. FOX, OF GRAND RAPIDS, MICHIGAN.

TYPE-BAR AND HANGER AND METHOD OF CONSTRUCTING SAME.

No. 852,428.

Specification of Letters Patent.

Patented May 7, 1907.

Application filed June 7, 1906. Serial No. 320,673.

To all whom it may concern:

Be it known that I, WILLIAM R. FOX, a citizen of the United States, residing at Grand Rapids, in the county of Kent, State of Michigan, have invented certain new and useful Improvements in Type-Bars and Hangers and Method of Constructing the Same, of which the following is a specification.

This invention relates to an improved type-bar hanger for typewriting machines and the method and means of constructing the same. It relates more particularly to an improved method and means of manufacturing the improved type-bar hanger described in Letters Patent No. 656,785, August 28th, 1900, to Fox *et al.*

The objects of this invention are to produce a type-bar hanger in which the parts shall be a close fit when the type is thrown to the printing point, and shall have a free movement when the type is at rest in the basket.

Further objects relate to the details of the manipulation of the hanger in conjunction with the pivot of the type-bar, and the proper formation of the same.

Objects relating to details will definitely appear from the detailed description to follow.

30 I accomplish the objects of my invention by the devices and means described in the following specification.

The invention is clearly defined and pointed out in the claims.

35 My improved typebar and hanger and structures for carrying out my improved method in the process of construction are clearly illustrated in the accompanying drawing forming a part of this specification, in which:

40 Figure 1 is a vertical sectional view of a press and die in which the initial forming process is carried out, taken on a line corresponding to line 1—1 of Fig. 2; Fig. 2 is a plan view of the said press; Fig. 3 is a sectional view of a similar press made use of in a succeeding state of manufacture, taken on a line corresponding to line 3—3 of Fig. 4; Fig. 4 is a plan view of the structure and 45 press appearing in Fig. 3; Fig. 5 is an enlarged detail transverse sectional view, taken on a line corresponding to line 5—5 of Fig. 4, showing the method of operation of the said press; Fig. 6 is a blank of the hanger B; Fig. 50 7 is a view of the hanger at the next step of its formation, showing the seat b; Fig. 8 is an

enlarged detail sectional view taken on line 8—8 of Fig. 2, showing the method of closing and forming the blank B as to the first step; Fig. 9 is an enlarged and elevation view of the 60 typebar with its projecting conical pivots; Fig. 10 is an enlarged detail side elevation view of the typebar and pivot; Fig. 11 is an enlarged detail sectional view showing the last step in the method of manufacture taken, on 65 a line corresponding to line 3—3 of Fig. 4; and Fig. 12 is an enlarged detail view of the completed type-bar and hanger, the adjusting screw merely being omitted.

In the drawing, the sectional views are 70 taken looking in the direction of the little arrows at the ends of the section lines, and similar letters of reference refer to similar parts throughout the several views.

Referring to the lettered parts of the drawing: The press A is provided with a suitable lever A' for acting upon the hanger B. A die-plate A'' is placed on top of the press, and a plunger bar a, carrying pivot-like projections a' a' at each side of the upper end thereof, is provided, which upper end extends up through the top of the die-plate A''. A recess is formed across the plate A'' which is curved downwardly at the central part (see details in Fig. 8) into which the hanger B is 85 forced by the pressure on the lever A'. An adjustable stop a'' limits the movement of the lever A' to prevent folding the blank too far at this stage of the manufacture.

The hanger blank B is punched from sheet 90 metal, as indicated in Fig. 6, and a recess b is cut into each side to receive the pivot pin of the typebar when the said hanger is folded. The blank as illustrated in Fig. 7 is inserted into the die-appearing in Fig. 1, the same being put down over the pivot pins a' a' longitudinally and then turned at right angles to locate the said pivots a' a' properly within the recess b. The lever A' is then depressed until it strikes the stop A'' when the blank 95 will be partially folded, as clearly appears in Fig. 8, the folded blank being indicated by dotted lines. This will not close the recess b around the pivot but will partially conform to the same, and permit the easy removal of the pivot pin a'. The hanger is then placed around the pivot c c of the typebar, and the operation is completed in the press D which is especially adapted and designed for that purpose.

100 A die-plate D'' is provided, which is of such configuration that the folded hanger can

- descend deep into the same and compress the opposite sides into substantially parallel relation with each other, they coming together at a very acute angle to permit of their adjustment by a proper set screw. The die-plate D'' is slotted to permit the depression of the type-bar into the same, but the sides are conformed to engage and fold the type-bar hanger.
- 10 On top of the die-plate D'' are oppositely arranged plates D''' D''' which serve to guide and properly locate the hanger between them in the operation of folding. In these plates D''' D''' are oppositely arranged pins E E' with suitable buttons on their outer ends for manipulating the same, the pin E' being withdrawn by a spring e'. The pin E is shorter than the pin E' and a pin e is provided in the same recess, the same being of a 15 length substantially the same as the width of the hanger so that it can be depressed through the opening in the die-plate E''.
- When the hanger is partially folded it is then placed on the typebar and the typebar 20 and its hanger are brought into position, as indicated by dotted lines in Fig. 5. The slot C' in the typebar for the key-lever connection is then brought opposite the pin e and the coupling d from the lever D' of the press 25 is bifurcated and raised up to embrace the short end of the lever of the typebar. The pin e is then pushed through and couples the plunger d to the typebar. The lever D' is then depressed and, owing to the fact that 30 the plunger d is coupled to the typebar by the pin e, the typebar hanger is drawn down into the die—and in this way the metal of the hanger is folded tightly around the pivot of the typebar, the movements of the lever being 35 continued until it comes into contact with the stop F which is adjustable to the right position for properly closing and folding the opposite sides of the typebar hanger together. The part is then raised up, the pin 40 e forced out of its connection by the pin E' being forced into the same, which carries the pin E back and the spring e' returns the pin E' to its proper position, when the typebar with its hanger can be lifted and raised from 45 the die and will be ready to receive its set-screw. The hanger is folded onto the typebar pivot by this means. By this method it will also be noted that the hanger is folded onto the typebar pivot when the typebar is 50 in a position of rest or in its initial position in the hanger. This is of great advantage because of the great difficulty of forming the pivots c on the typebar perfectly; and it will be noted that if there are any slight imperfections in the pivot that the pivot will fit more closely in its bearing when the typebar is moved from the position in which the hanger is formed onto the same—so that by 55 this method, the typebar will be perfectly free in the basket and will come to a tight fit.

at the printing point, the tightness of the fit being very readily regulated by the set-screw of the bearing. The hanger may be wrapped around the pivot by holding the pivot against the recess b, then folding the hanger around the pivot. The first operation of bending, as shown in Fig. 8, may be omitted entirely and the bar and pivot used to bend the blank from the form shown in Fig. 7 to that of B in Fig. 11. The first operation is ordinarily of advantage. It will be seen, therefore, that by this method of forming the typebar and hanger a result is secured of having very free pivotal movement of the same with a very close joint at the printing point,— 70 and yet the closeness of the fit of the joint can be regulated so that the movement is, for all practical purposes, perfect. Also, by this method, it is possible to manufacture the typebar hanger by wrapping the soft steel 75 hanger around the hardened pivot and thereby securing a perfect fit of the parts,—which has been found impossible to accomplish by machining operations because on such very small articles, where the conical fit is desired, it is a matter of the greatest difficulty to get a bearing for the pivot that will exactly conform, or to finish the pivot so perfectly that it will exactly fit the bearing; whereas, by my method herein set forth, substantially perfect pivoting of the typebar can be secured with great ease and rapidity, and the slight irregularity of the pivot pin which is almost unavoidable is utilized in securing the very free pivoting of the typebar while in motion and a snug fit of the same at the printing point,—advantages which will appeal to anyone familiar with the manufacture of typewriters. 90

Having thus described my invention, what I claim as new and desire to secure by Letters Patent is:

1. The combination with a type bar C with laterally extending pivots therefor, of a hanger folded about and conformed to the said pivots and adapted to be adjusted thereon, the same being folded and conformed onto the pivots, with the typebar arranged at the angle of the position of rest, whereby irregularities of the pivot are impressed into the bearing and are utilized for securing a tight joint at the printing point and a free pivoting at other points, as specified. 110
2. The combination with a type-bar C with laterally extending pivots therefor, of a hanger folded about and conformed to the said pivots with the typebar arranged at the angle of the position of rest, whereby the irregularities of the pivots are impressed into the bearing and are utilized for securing a tight joint at the printing point and a free pivoting at other points, as specified. 115
3. The combination with a typebar C with laterally extending pivots therefor, of a 120

hanger folded about and conformed to the said pivots, whereby the bearing is accurately conformed to the pivots; as specified.

4. The method of forming a hanger and typebar in conjunction, consisting in forming a flat blank from sheet metal, bifurcated, with recesses to receive a laterally projecting pivot on the typebar, partially folding the said blank by means of a plunger and enlarged pivots by drawing the said pivots against the recessed part, then substituting the typebar with its pivots and connecting a plunger to the short arm of the typebar and drawing the blank into a recess so that it is folded by the pressure of the pivot in the recess, the said typebar being arranged at the angle of rest during the process, as specified.

5. The method of forming a hanger and typebar in conjunction, consisting in forming a flat blank from sheet metal, bifurcated, with recesses to receive a laterally projecting pivot on the typebar; partially folding the said blank by means of a plunger and enlarged pivots by drawing the said pivots against the recessed part, then substituting the typebar with its pivots and connecting a plunger to the short arm of the typebar and drawing the blank into a recess so that it is folded by the pressure of the pivot in the recess, as specified.

6. The method of forming a typebar and hanger, consisting in stamping a flat blank, bifurcated, with recesses for receiving the

opposite ends of the pivot, and engaging the pivot of the said typebar in said recess and compressing the hanger into a suitable forming die by compressing the pivot against the same, the said typebar being arranged at the angle of rest during the process, co-acting as specified.

7. The method of forming a typebar and hanger, consisting in stamping a flat blank, bifurcated, with recesses for receiving the opposite ends of the pivot, and engaging the pivot of the said typebar in said recess and compressing the hanger into a suitable forming die by compressing the pivot against the same, co-acting for the purpose specified.

8. The method of forming a hanger around a pivot in a typebar, consisting in stamping a flat blank bifurcated with recesses for receiving the opposite ends of the pivot and engaging the pivot, the hanger being folded around said pivot, forming a bearing for the same, as specified.

9. The method of forming a hanger consisting in folding the bifurcated hanger around a pivot, whereby the bearing is accurately conformed to the pivot as specified.

In witness whereof, I have hereunto set my hand and seal in the presence of two witnesses.
